E. BOMMER

DOOR CLOSER

Filed July 1, 1924

INVENTOR
Emil Bommer,

By C. P. Goefel
ATTORNEY

UNITED STATES PATENT OFFICE.

EMIL BOMMER, OF BROOKLYN, NEW YORK.

DOOR CLOSER.

Application filed July 1, 1924. Serial No. 723,598.

To all whom it may concern:

Be it known that I, EMIL BOMMER, a citizen of the United States, and a resident of Brooklyn, county of Kings, and State 5 of New York, have invented certain new and useful Improvements in Door Closers, of which the following is a specification.

This invention relates to door closers and has for its primary object to provide a 10 simple and inexpensive device including a part adapted to be adjustably positioned with relation to the door whereby resistance may be offered to the swinging movement of the door from its closed towards an open 15 position, or on the other hand, the door may be permitted to swing freely without such resistance.

With the and other objects in view, I 20 have illustrated one practical embodiment of my invention in the accompanying drawing which will be hereinafter more fully described and subsequently incorporated in the subjoined claims.

In the drawing wherein similar reference 25 characters designate corresponding parts throughout the several views:

Figure 1 is a fragmentary elevation of a door and part of the door jamb with my device applied thereto;

Figure 2 is a bottom plan view partly 30 broken away;

Figure 3 is a fragmentary perspective view of the essential portion of the device;

Figure 4 is an enlarged detail perspective view of one of the parts;

Figure 5 is a transverse section taken on the line 5—5 of Figure 4; and

Figure 6 is a sectional view taken on the line 6—6 of Figure 5.

Referring in detail to the drawing, 5 designates a part of the door which is hingedly mounted at one of its edges for swinging movement relative to the door jamb 6.

Upon the jamb 5 the bracket plate 7 is secured by screws 8, said bracket plate having horizontal outwardly projecting ears 9 and 10 respectively at its upper and lower ends.

Between these ears the cylindrical barrel or housing 11 for a coil spring is arranged. Between the opposite ends of the cylindrical barrel 11 and the ears 9 and 10 respectively, the collars 12 and 13 are arranged, one end of the spring within the barrel being connected to the collar 12. The construction, mounting and arrangement of the parts 11,

12 and 13 with the spring contained in said barrel is well known in the art of spring hinges, and therefore, need not be further described. For the present explanation, it 60 will suffice to state that the collar 12 has a laterally projecting arm 14 thereon, the lower side of which has a groove or channel 15 therein, the side walls of said channel being connected at their upper edges at the 65 end of the arm as at 16. At the inner end of the channel the lower wall thereof provides a seat 17, the surface of said seat having a transverse groove or channel 18 cut 70 therein.

A rod 19 has each of its ends upset or enlarged as indicated at 20 and 20^a, respectively. When the rod is disposed in a horizontal position, one of its ends is seated upon the seat 17 of the arm 14 and the enlargement on the ends of the rod is engaged in the groove 18 of said seat. As illustrated, I have shown the device mounted upon the left hand jamb of the door and therefore, the enlarged end 20 of the rod is engaged in 80 said groove. When the rod is in its horizontal position, such enlargement prevents longitudinal movement of the rod upon its seat and when the rod is disengaged from said seat, it is slidably moved with respect to the arm 14, the enlargement 20 engaging the one side of the arm to limit such sliding movement of the rod and sustain said rod in a pendant vertical position. When the bracket and collar 12 are arranged upon 85 the right hand door jamb, they are inverted from the position shown in the drawing and in such case the other enlarged end 20^a of the rod 19 serves to limit sliding movement of the rod to its vertical position and prevent disconnection of said rod from the arm. 90

Upon the face of the door 5, a roller 21 is mounted in a suitable bracket 22, said roller being peripherally grooved and the rod 19 when in a horizontal position, being held in 100 this groove of the roller by the spring contained in the barrel 11, which spring is connected to the collar 12.

From the above description, it will be readily seen that when the rod 19 is disposed as shown in Figure 1 of the drawings so that it bears against the grooved roller 21 and the end thereof is locked in connection with the arm 14 on the collar 12, when the door 5 is swung towards an open position, 105 the roller 21 will ride along the rod as said rod is swung laterally with the door. In 110

such swinging movement of the door and the rod the collar 12 is rotated so that the spring in the barrel 11 is placed under a gradually increasing tension. Therefore, a 5 gradually increasing resistance is applied as the door is moved towards its extreme open position.

When it is desired to permit of the free swinging movement of the door without such 10 resistance, it is only necessary to disengage the flange 20 on the end of the rod 19 from the groove 18 and then move the outwardly projecting part of the rod downwardly, thus swinging the end of the rod having the 15 flange 20 upwardly in the channel 15 of the arm 14 so that said rod will hang loosely in perpendicular position, as shown in dotted lines in Figure 1 of the drawings with the flange 20 engaged upon the side of the arm 20 14. Thus the rod is supported closely adjacent to the face of the door jamb and out of the path of movement of the door so that the latter may be freely swung to any desired degree towards its open position and 25 remain in such position.

The device as above described can be applied to the jamb at either the right or the left side of the door, it being only necessary to invert the position of the device so that 30 the arm 14 will be at the lower end thereof when the device is applied to a right hand jamb.

As above explained the rod 19 cannot become disconnected from the arm 14 in either 35 position of said arm upon the right or left hand door jamb by reason of the enlarged ends 20 and 20^a of said rod, and it is understood of course that the roller 21 is properly positioned on the door face so that the rod 40 will engage therewith when disposed in its horizontal position.

From the foregoing description considered in connection with the accompanying drawings, the several essential features of 45 the device will be clearly understood together with the advantages thereof. Owing to the simple form and construction of the several co-operating elements it will be seen that such a device is exceedingly durable, 50 not likely to get out of order and positive and reliable in the performance of its functions.

While I have herein shown and described a preferred embodiment of my invention, it 55 will nevertheless be understood that the same is susceptible of embodiment in other alternative constructions, and I therefore reserve the privilege of resorting to all such legitimate changes as may be fairly embodied within the spirit and scope of the invention as claimed.

I claim:

1. In combination, a spring held member mounted upon a door jamb for movement 60 in a horizontal plane and having a later-

ally projecting arm formed with a longitudinal channel having a seat at the inner end thereof, a rod provided with an enlarged head on one end and adapted for engagement upon said seat when said rod 70 is disposed in a horizontal position, a roller mounted on the door face with which said rod is engaged when in horizontal position under tension whereby in the swinging movement of the door, said spring held member 75 is rotated and resists said swinging movement of the door, said rod adapted to be moved from said horizontal position to a vertical position and the enlarged head on the end of the rod engaging the upper side 80 of said channel arm to sustain the rod in such vertical position.

2. In combination, a spring held member mounted upon a door jamb for rotary movement in a horizontal plane and having 85 a laterally projecting arm provided with a longitudinal channel open on one side and having a seat at the inner end thereof, said arm having a connection between the side walls of said channel at the outer end of 90 the arm, and at the side of said channel, said seat having a groove in the walls thereof, a rod having an enlargement on each end, one end of the rod adapted for engagement upon said seat with the enlargement 95 thereof seated in said groove to prevent longitudinal shifting movement of the rod when in a horizontal position, a roller mounted on the door face with which said rod is engaged under tension in the latter 100 position whereby in the opening swinging movement of the door said member is rotated against the resistance of the spring to thereby apply a gradually increasing resistance to said swinging movement of the door, said rod adapted to be moved from such 105 horizontal position to a vertical position beyond the door edge, and the other enlarged end of the rod engaging the other side of said arm to sustain the rod in its vertical 110 position and prevent it from becoming disassembled when the spring member is arranged with the projecting arm at its lower end.

3. In combination, a bracket and a spring held collar rotatably mounted in one end of said bracket, said bracket and collar being invertible for arrangement upon either a right or left hand door jamb, said collar having a laterally projecting arm thereon, a rod slidably and permanently connected with said arm and having an enlargement formed on each of its ends, said arm having a seat upon which one end of said rod is adapted to be engaged and a groove formed in said seat to receive the enlargement on one end of the rod when said rod is disposed in a horizontal position, said rod when 125 disengaged from said seat being slidable with respect to said arm and the enlarge- 130

ment on one end of said rod coacting with the arm to prevent disconnection of the rod therefrom and sustain said rod in a pendent vertical position, and a roller adapted to be mounted on the face of a door to engage said rod when the rod is horizontally positioned with respect to said arm.

4. In combination, a spring, a member held thereby and adapted for movement in a horizontal plane against the resilient action of the spring, a lateral projection extending from said member, an arm carried by said projection with one or the first end engaging the projection and its other or second end hanging downwardly therefrom, and means for holding said arm in said projection so as to project laterally thereof by positioning the arm therein with the said second end thereof engaging said projection and its first end extending laterally outward therefrom.

5. In combination, a spring, a member held thereby and adapted for movement in a horizontal plane against the action of the spring, a laterally projecting arm formed

with a longitudinal channel having a recess providing a socket in the inner end thereof, a rod provided with an enlarged head on one end and adapted for engagement upon said socket when said rod is disposed in a horizontal position and adapted to be moved from said horizontal position to a vertical position and the enlarged head on the end of the rod engaging the upper side of said channel arm to sustain the rod in such vertical position.

6. In combination, a spring, a member held thereby and adapted for movement in a horizontal plane against the resilient action of the spring, a lateral projection extending from said member, an arm slidingly carried in said extension adapted to extend horizontally therefrom and to slide therein so that either of its ends will engage said extension and means on the ends of the arm to prevent its removal from said extension.

In testimony that I claim the foregoing as my invention, I have signed my name hereto.

EMIL BOMMER.
